UNITED STATES PATENT OFFICE.

EZRA H. TRAUT, OF FRANKLIN, PENNSYLVANIA, ASSIGNOR OF FORTY-FIVE ONE-HUNDREDTHS TO LEWIS OVERTURF, OF FRANKLIN, PENNSYLVANIA.

RAIL-TIE FASTENER.

1,230,630.

Specification of Letters Patent. Patented June 19, 1917.

Application filed June 27, 1916. Serial No. 106,211.

To all whom it may concern:

Be it known that I, EZRA H. TRAUT, a citizen of the United States, residing at Franklin, in the county of Venango and State of Pennsylvania, have invented new and useful Improvements in Rail-Tie Fasteners, of which the following is a specification.

This invention relates to railway ties, and track fastenings therefor.

10 The object of the invention is to provide means whereby the distance between two parallel rails may be varied to make provision for wear on the rails, etc.

Another object is to provide means whereby the rail may be easily attached to the tie and securely held against accidental displacement, but capable of accomplishing fine lateral adjustment of a rail.

Besides the above my invention is distinguished in the novel manner of associating the cam with the clamping jaws so that fine lateral adjustment of a rail can be accomplished while at the same time the jaws will be prevented from wedging upwardly 25 away from the tie.

It is also the object of my invention to provide means whereby the fastening device or devices will not readily become loose, due to the jarring or vibration of the rails 30 or from any other cause.

I also aim to provide means for securing the rails, which means may be simple in operation, inexpensive to manufacture, and durable when in use.

35 Other objects and advantages of this invention will appear hereinafter, it being understood that changes in form, proportion and minor details of construction may be resorted to without departing from the 40 spirit of the invention or sacrificing any of its advantages.

In the drawings:

Figure 1 is a plan view of one end of a tie, and rail fastening device embodying my 45 invention.

Fig. 2 is a longitudinal sectional view through one end of the tie and a cross sectional view through the rail.

Fig. 3 is a detail view of a washer or disk 50 forming part of the fastening device.

Fig. 4 is a cross sectional view through

the tie showing the rail and fish plates, in side elevation.

Fig. 5 is a cross sectional view through the rail and fish plates, the fastening device 55 being shown in cross section and the tie in longitudinal section.

Fig. 6 is a detail view of a tool or wrench for adjusting the fastening device.

Fig. 7 is a plan view of a modified form of 60 my invention and,

Fig. 8 is a view partly in section and partly in elevation showing a construction to be utilized in connection with wooden ties.

For the purpose of illustration I have 65 shown but one end of a tie in Figs. 1 and 2, this being sufficient as each end is a duplicate of the other.

The intermediate portions 1, of the tie is shown as consisting of a substantially T- 70 beam form.

The respective ends of the ties are of box girder form and are here designated 2. From the extremities of the box girders 2 project flanged ends 3. 4 designates a rail 75 resting upon the top of the girder 2, and between two substantially parallel gibs or clamping jaws 5 and 6 which engage the flanges of the rail (best shown in Fig. 2).

Each gib is formed with curved recesses 7 80 and 8, one above the other and the latter of a greater radius than the former to form a ledge 8^a. The cam members 9 and 10 are provided for the gibs and each is formed to have a cam face 11 coöperating with the 85 walls of the recess 7 and a second cam face 12 arranged beyond the cam face 11 and co-operating with the walls of the recess 8.

From this arrangement it will be seen that a flange 11 is formed between the cam face 90 and bears upon the ledge 8^a for preventing the wedging upwardly of a gib during the operation of the cam member. This is a very important feature as it allows fine lateral adjustment of a rail and at the same time 95 maintains the proper relation between the rail, gib, and cam member.

The cam member is formed with an extension 13 seated in a circular opening 14 in the girder so that the cam member will 100 be free to rotate. The lower end of the extension has formed therein a slot 15 receiv-

ing a rib 16 formed upon a disk 17 of a diameter to overlap the opening 14. Extending through the cam member extension and disk is an opening 19 receiving a bolt 20 that has its head in abutting relation with the disk and a nut arranged in the recess 18 in the cam member. The nut 21 of the bolt is snugly received in the recess and the latter is closed by a cap 22.

10 At this point I wish to call attention to the fact that the construction of the girder and the arrangement of the parts of the fastener is such that the bolt may be readily loosened and the cam member rotated for 15 giving the proper adjustment to the rail and owing to the manner of mounting the cam member any degree of adjustment can be accomplished.

In Figs. 4 and 5, I have shown the device 20 attached to a tie in the form of a commercially rolled channel 23, and instead of the cam engaging the flange on the rail, fish plates 24 and 25 are provided which are connected to the rails by the usual bolts 26. 25 The bases of the fish plates are engaged by the cams in the same manner as they engage the flanges of the rails according to Figs. 1 and 2.

In Figs. 7 and 8 I have shown a plate 27, 30 adapted to be fastened to a wooden tie, 28 and this plate is provided with recesses 29 to accommodate the disk 17. The plate 27 may be fastened to the tie in any convenient manner, the rail engaging fastenings being 35 adapted to be connected to seat plate in substantially the same way they are connected to the girder portions of the tie 1 in Figs. 1 and 2.

In Fig. 6 I have shown a wrench or tool 40 30 having a handle 31, an angular end 32 engaging the socket 18 to turn the cams for the purpose of taking up wear, etc., on the rail. Thus the track walker may operate the cams in a convenient manner.

45 By reference to Fig. 4 it will be observed that the fish plates are provided with lugs 33, the purpose of which is to prevent the creeping of the rail. The lugs 33 project from the bottom of the fish plates and snugly 50 set against opposite sides of the tie 23 whereby any tendency of end movement of the rail will be opposed by the tie.

Attention is also called to the fact that in the construction of the tie shown in Figs. 1 55 and 2, the box girder 2 constitutes what might properly be termed resilient chair or seat whereby the tie has the advantage of a metallic construction and the resiliency of wood.

60 From the foregoing it will be apparent that the device is effective in operation, simple in construction and will be durable when in use.

I claim—

65 1. A rail fastening device comprising a

metallic base, having an opening, a two part fastener in the opening comprising a cam, having a reduced part forming a swivel and a disk having rib engaging a groove or slot in the lower part of the cam and means for 70 fastening the two together.

2. A fastening device for rails comprising a cam, having a recess, a cap for the recess, a disk, means on the disk for engaging a slot in the cam and a bolt running through the 75 cam and the disk.

3. A rail fastening comprising a cam having a top flange greater in diameter than the cam, a reduced part on the cam for engagement with an opening in a support, a 80 disk having a flange and a rib on the disk to engage a slot on the cam, and a bolt passing through the cam and the disk.

4. In combination with a rail tie and a rail upon the tie, a fastening device consisting of a gib engaging the rail flange and a cam locking device engaging at least two different surfaces of the gib for accomplishing lateral adjustment of the rail. 85

5. In combination with a rail tie and a rail 90 upon the tie, a fastening device consisting of a gib engaging the flange of the rail and having a pair of arcuate recesses, one above the other and means including a cam having a duplex cam surface engaging the walls of 95 the recess for accomplishing lateral adjustment of the rail.

6. In combination with a rail and a metallic rest for the rail provided with a circular opening, a gib bearing upon the flange 100 of the rail, a fastening device rotatably mounted in the opening and having a lateral cam action with the gib and overlapping the same.

7. In combination with a rail and a metallic rest for the rail provided with a circular opening, a gib bearing upon the flange of the rail, a fastening device rotatably mounted in the opening and having a lateral cam action with the gib in a direction 110 toward the rail and overlapping the gib, and means operated from a point beneath the rest for detachably mounting the device in the opening. 105

8. In combination with a rail and a metallic rest for the rail provided with a circular opening, a gib bearing upon the flange of the rail, a fastening device rotatably mounted in the opening and having a lateral cam action with the gib and overlapping the 120 same, means operated from a point beneath the rest for detachably mounting the device in the opening, each end of said gib being shaped to engage two of the sides of the rests and allow movement of the gib upon the 125 rest in a direction away from the rail.

9. In combination with a rail and a rectangular member supporting the rail, a gib engaging the base of the rail and having an end bent to engage opposite sides of the 130

member and locking means engaging a side and top of the gib and capable of giving lateral movement thereto.

10. In combination with a rail and a rectangular member supporting the rail, a gib 5 engaging the base of the rail and having an end bent to engage opposite sides of the member and locking means engaging a side and top of the gib and capable of giving

lateral movement thereto, said locking means 10 having engagement with and rotatably mounted in the member.

In testimony whereof I affix my signature in presence of two witnesses.

EZRA H. TRAUT.
